POWER TRUCK

Wesley Max Walker, Fowler, Kans., assignor to Walker
Manufacturing Company, Fowler, Kans., a partnership

Filed Sept. 24, 1962, Ser. No. 71,829

Term of patent 14 years

(Cl. D14—3)

Fig. 1.

Fig. 2.

Fig. 3.

Fig. 4.

FIG. 1 is a perspective view of a power truck, showing my new design.

FIG. 2 is a front perspective view thereof;

FIG. 3 is a perspective view showing the steering wheel pivoted to the right side; and

FIG. 4 is a rear perspective view of a power truck.

I claim:

The ornamental design for a power truck, as shown.
